UNITED STATES PATENT OFFICE.

HERBERT E. IVES, OF MONTCLAIR, AND MAURICE B. LONG, OF GLEN RIDGE, NEW JERSEY, ASSIGNORS TO WESTERN ELECTRIC COMPANY, INCORPORATED, OF NEW YORK, N. Y., A CORPORATION OF NEW YORK.

TRANSMISSION OF PICTURES BY ELECTRICITY.

Application filed May 14, 1924 Serial No. 713,362.

This invention relates to the transmission of pictures by electricity and more particularly to a system having a linear transmission characteristic.

In a copending application of M. B. Long, Serial No. 681,347, filed December 18, 1923, and patent to E. C. Wente, No. 1,686,355, Oct. 2, 1928, systems for transmitting pictures by electricity are disclosed. In these systems, a 10 voice frequency carrier wave is modulated by amplified current from a photoelectric cell which itself is variably excited by light intensities corresponding to the tone valves of elemental areas of the picture. The picture 15 is reproduced from the modulated wave by a light valve. In the Wente arrangement, the modulated wave is impressed directly upon the movable conductors of the light valve. Unless suitable precautions are taken distortion 20 may be introduced by the circuit elements and lack of faithfulness of reproduction will result.

An object of this invention is to obtain 25 faithfulness of reproduction. Another object is to obtain this result by operating each circuit arrangement linearly.

These objects are attained in one embodiment of the invention by operating each circuit element within a finite limiting range 30 between the extremities of which the characteristic of the arrangement is linear. The current from a photo-electric cell is first amplified by a two-stage electron discharge amplifier after which it is impressed upon an 35 electron discharge modulator in order to modulate a voice frequency carrier wave. After transmission to the reproducing terminal, the modulated wave is amplified and impressed upon the movable conductor of a 40 single string light valve. The movement of the string causes the exposure of a light sensitive record blank to reproduce the picture. The adjustment is such that the voltage impressed upon the first stage of the amplifier is directly proportional to the light incident 45 upon the photoelectric cell and the current output from each stage of the amplifier and from the modulator is directly proportional to the voltage impressed upon the respective 50 devices within the limits of the light incident upon the cell. This results in the carrier wave having a finite amplitude greater than zero at both limits of its working range. The light valve is provided with adjustable jaws

so that any desired amplitude of vibration of the string may be required before any exposure of the record blank results. Thus, the non-exposure and full exposure conditions of the light valve may be made to correspond to the light and dark conditions of the photoelectric cell.

The term "light" as used herein includes not only radiations within the visible spectrum but also radiations having wave lengths above and below those of the visible spectrum.

It is to be understood that the terms used herein, both in the specification and claims, do not limit this invention to the production of a picture record at the receiver from a picture record at the transmitter. The invention is equally applicable to systems, for example, in which a transitory image is produced at the receiver, as in certain forms of television systems.

The novel features which are considered 75 characteristic of this invention are set forth with particularity in the appended claims. The invention, both as to its organization and method of operation together with other objects and advantages thereof, will be further 80 explained in the following description, having reference to the accompanying drawing consisting of the following figures.

Fig. 1 is a schematic circuit arrangement of a sending terminal according to this invention.

Fig. 2 is a schematic circuit arrangement of a reproducing terminal to cooperate with the arrangement of Fig. 1.

Fig. 3 is a top view of the optical arrangement of Fig. 2 partially in cross section.

Figs. 4 and 5 are fragmentary views of details of the light valve greatly enlarged.

Fig. 6 shows characteristic curves of the circuit elements of the sending equipment.

Fig. 7 illustrates schematically an arrangement for rotating the picture drum and simultaneously moving it axially.

A system according to this invention is illustrated by placing Figs. 1 and 2 side by side from left to right, respectively.

Referring to the drawing so arranged, a sending drum 5 at the sending terminal carries a transparency of the picture to be transmitted. A receiving drum 6 at the reproducing terminal carries a light sensitive record blank. The picture drums 5 and 6 are driven synchronously and moved axially

by a suitable synchronizing system such for example, as that disclosed in the Long application supra. Within the sending drum 5 a photoelectric cell 7 is located which is connected to the input circuit of electron discharge device 8 by photoelectric cell battery 9 and coupling resistance 10. The electron discharge device 8 with its associated input and output circuits forms the first stage of a two-stage picture current amplifier PCA. The second stage of this amplifier consists of electron discharge device 11. Device 11 is coupled to device 8 through battery 12 and coupling resistance 13. The current in the photoelectric cell 7 is controlled by light from source 14 directed by lens 15 through an aperture in shield 16 and the transparency of the picture on drum 5.

An electron discharge modulator M is coupled to a source of voice frequency carrier waves CO by means of transformer 17 and resistance 18. The modulator M is also connected to the output circuit of amplifier PCA through battery 19 and resistance 20. The output circuit of the modulator M is coupled to a transmission line L by means of transformer 21. At the receiving terminal, the modulated carrier waves from the line L are amplified in a two-stage electron discharge amplifier RA and impressed upon string 22 of light valve V. The amplifier RA consists of two electron discharge devices 23 and 24 with their associated input and output circuits. The coupling between the input circuit of device 23 and the line L consists of potentiometer 25 and transformer 26. The coupling between the output circuit of device 24 and the light valve V is through transformer 27. The vibration of string 22 with respect to aperture forming jaws 28 and 29 determines the amount of exposure of the record blank on drum 6 in an axial direction. The aperture in shield 30 determines the amount of exposure in the direction of rotation of the record blank.

The string 22, the jaws 28 and 29 and the screen 30 will hereinafter be designated as the aperture forming members. The jaws 28 and 29 define what will be called hereinafter the horizontal aperture. The aperture in screen 30 will be called the vertical aperture.

The aperture forming members are intensely and uniformly illuminated by light from source 31 passing through lens 32. The area illuminated is at least as large as the largest opening defined by jaws 28 and 29 and screen 30. An image of the aperture formed by the aperture forming members is projected upon the record blank on drum 6 by lens 33.

An arrangement for rotating the picture drums and simultaneously moving them axially is illustrated in Fig. 7. It will be described with reference to the sending drum 5, but it is to be understood that a similar

arrangement may be used at the reproducing terminal. The drum 5 is mounted on a shaft 53, which is carried by carriage 51 which itself is movable with respect to the frame 50. The shaft 52 rotates, but is fixed longitudinally with respect to frame 50. It has screw engagement, however, with carriage 51 which is moved along frame 50 by the rotation of shaft 52. Shaft 53 is driven by shaft 52 through gear wheels 54 and 55. Gear wheel 54 is slidably mounted on shaft 52, but rotates with it due to a key which slides in a keyway.

Referring again to Fig. 1, the potential impressed between the grid and filament of device 8 is represented by E-1 and its value is determined by the potential of battery 38 and the potential drop across resistance 10 due to current I-0 flowing through resistance 10. The potential impressed between the grid and filament of device 11 is represented by E-2, and its value is determined by that part of the battery 12 which is connected into the input circuit of device 11 and the potential drop across resistance 13 due to current I-1 flowing in resistance 13. The potential impressed upon the modulator M, exclusive of the potential of the carrier wave from source CO, is represented by E-3 and its value is determined by that portion of battery 19 connected in the input circuit of modulator M and the potential drop across resistance 20 due to current I-2 flowing in resistance 20. The amplitude of the current flowing in the line L is represented by I-L.

Referring now to Fig. 6, the characteristics of the elements of Fig. 1 are shown by curves A, B, C, D, E, F, and G.

Curve A shows the value of current I-0 flowing in resistance 10, corresponding to different values of light intensities incident upon the photoelectric cell 7. Under the dark condition which is obtained when an opaque screen is inserted between the source of light 14 and the photoelectric cell 7, the value of I-0 is zero. For the light condition, which may correspond to the maximum intensity of light from the source 14 or any other intensity desired, current I-0 corresponds to the ordinate of the point a. The slope of the curve A is dependent upon the potential of battery 9 and the value of resistance 10. Between these two limiting conditions and for some distance beyond the curve A is linear.

Curve B shows the relation between the potential E-1 impressed upon the input circuit of amplifier 8 and the current I-0 flowing in the resistance 10. The point b corresponding to the dark condition is dependent upon the potential of battery 38 which is represented by the line O-b. The point c corresponding to the light condition, or the point a on curve A, is determined by the magnitude of the resistance 10. Thus the slope of

the curve B is determined by the magnitude of resistance 10.

Curve C shows the relation between the potential E-1 impressed upon the input circuit of amplifier 8 and the current I-1 flowing in the resistance 13. Point *d* corresponds to the dark condition of curve A, or point *b* of curve B. Point *e* corresponds to the light condition, or the point *a* of curve A, or the point *c* of curve B.

Curve D shows the relation between the potential E-2 impressed upon the input circuit of amplifier 11 and the current I-1 flowing in the resistance 13. Point *f* corresponds to the dark condition of curve A and point *g* to the light condition. The slope of curve D is determined by the value of resistance 13 while the intersection with the abscissa at *h* is dependent upon the potential of battery 12 which is included in the input circuit of amplifier 11.

Curve E shows the relation between the potential E-2 impressed upon the input circuit of amplifier 11 and the current I-2 flowing in the resistance 20. The shape and slope of the curve E is dependent upon the physical characteristics of the device 11 and the value of resistance 20. The points *k* and *m* correspond to the dark and light conditions respectively of curve A.

Curve F shows the relation between the potential E-3 impressed upon the input circuit of modulator M, exclusive of the potential due to the carrier source CO, and the current I-2 flowing in the resistance 20. The slope of curve F is dependent upon the value of resistance 20 while its intersection with the abscissa at point *p* is dependent upon the potential of that part of battery 19 connected in the input circuit of the modulator M. The points *t* and *n* correspond respectively to the dark and light conditions of curve A.

The curve G shows the relation between the input voltage E-3 and the amplitude of the current I-L flowing in the line L. The shape of this curve is dependent upon the physical characteristics of the modulator electron discharge device M and the amplitude of the carrier wave from the source CO. The point *s* corresponds to the dark condition and the point *r* to the light condition or point *a* of curve A. Between the points *r* and *s*, curve G is substantially linear. In order to operate only over the linear portion of curve G, it is necessary that the minimum amplitude of the carrier wave as delivered to the line under the light condition shall have a finite value greater than zero. Thus, in order that the amplitude of the carrier current delivered to the line shall bear a linear relation to the light intensities incident upon the photoelectric cell 7, the adjustment of the circuit elements must be such that the minimum value of carrier current has a

finite value above zero. The modulator may, therefore, be considered to have an electrical bias.

When this modulated carrier wave is impressed upon the string 22 of light valve V, the string 22 vibrates with an amplitude corresponding to the amplitude of the impressed current. In order to prevent the exposure of the record blank due to the amplitude of carrier wave corresponding to the point *r* of curve G, the light valve is mechanically biased by means of adjustable jaws 28 and 29, as shown in Fig. 5.

The horizontal aperture formed by jaws 28 and 29 is so adjusted that the string 22 will need to move a distance represented by the space 40 (Fig. 5) before an aperture will be formed through which light can pass to expose the record blank. Thus, the bias at the sending terminal which is necessary in order to obtain linear modulation is compensated for by bias at the reproducing terminal.

In the preferred arrangement this bias is effected by mechanical means.

The jaws 28 and 29 are made adjustable by mounting them on flexible supports 34 and 35 respectively. (Fig. 4.) These supports are minutely adjustable by screws 36 and 37 passing through posts 38 and 39. These jaws as well as the string 22 may be secured to the magnetic plate of the light valve V as disclosed in Patent No. 1,667,805, May 1, 1928, of applicant H. E. Ives.

This method of operating a transmission system is especially important in a commercial system using electron discharge devices. Such devices, when operated with any physically practicable adjustment have decided non-linear characteristics both at low and high values of impressed input potential. These characteristics can be made substantially linear only between certain finite limiting values, neither of which is zero. In a commercial system, however, it is highly desirable to be able to operate each element over the linear portion of its characteristic, since each element can then be independently adjusted, after which each element can be associated with the other elements of the system with the assurance that the combination will function to give faithful reproduction. This is especially important where the several elements in the system may be widely separated geographically.

Various modifications of the specific embodiment of the invention as hereinbefore described may be made without departing from the scope of the invention, as defined by the appended claims.

What is claimed is:

1. A method of signal transmission by carrier waves which comprises electrically biasing the modulator so as to operate over a linear portion of its signal input potential-output carrier amplitude characteristic, and

mechanically biasing the responsive device to compensate for the electrical bias of the modulator.

2. In a system for the transmission of pictures by electricity, an electron discharge modulator for modulating a carrier wave in accordance with the signal, said modulator having a characteristic between signal voltage impressed upon its input circuit and amplitude of carrier wave in the output circuit which is linear between two finite values, each greater than zero, a source of signal current for impressing potentials upon the input circuit of said modulator for operating over the linear portion only of said characteristic, and a receiver upon which said modulated wave is impressed, including biasing means for limiting the effect of said receiver to the linear portion only.
3. In a system for the transmission of pictures by electricity, an electron discharge modulator for modulating a carrier wave in accordance with the signal, said modulator having a characteristic between signal voltage impressed upon its input circuit and amplitude of carrier wave in the output circuit which is linear between two finite values, each greater than zero, a source of signal current for impressing potentials upon the input circuit of said modulator for operating over the linear portion only of said characteristic, and an electro-optical arrangement for obtaining light beams, the effect of which is proportional to the amplitude of the signal current.
4. In a system for the transmission of pictures by electricity, a photo-electric cell, an electron discharge amplifier for amplifying current from said cell, an electron discharge modulator for modulating a carrier wave in accordance with said amplified current, means to vary the light incident upon said cell between two finite values to vary the current in said cell, means to cause the potential impressed upon said modulator due to said amplified current to vary between two finite values, neither of which is zero, and a demodulator for said modulated carrier wave which gives no useful response for those amplitudes of carrier waves less than that corresponding to the smaller of the two limiting values of impressed potential.
5. In a system for the transmission of pictures by electricity, a photo-electric cell, an electron discharge amplifier for amplifying current from said cell, an electron discharge modulator for modulating a carrier wave in accordance with said amplified current, means to vary the light incident upon said cell between two finite values to vary the current in said cell, means to cause the potential impressed upon said modulator due to said amplified current to vary between two finite values, neither of which is zero, and a light valve actuated by said modulated wave and

adjusted to transmit no light when amplitudes of the carrier wave are less than that corresponding to the smaller of the two limiting values of the impressed potential.

6. In a system for the transmission of pictures by electricity, a photo-electric cell, a two-stage, electron discharge amplifier for amplifying current from said cell, an electron discharge modulator for modulating a carrier wave in accordance with said amplified current, means to vary the light incident upon said cell from zero to a finite value, means to cause the potential impressed upon said modulator due to the amplified current corresponding to varying light intensities incident upon said photo-electric cell to vary between two finite values, neither of which is zero, and a light valve actuated by said modulated wave and adjusted to transmit no light when the amplitudes of the carrier wave are less than that corresponding to the light condition of the photo-electric cell.

7. In a system for the transmission of pictures by electricity, a source of carrier waves, means to modulate carrier waves from said source to produce modulated carrier waves having amplitudes which vary between two finite limiting values, neither of which is zero, corresponding to variations in the tone values of elemental areas of a picture between black and white, and detecting means for producing from said modulated carrier waves a picture the tone values of the elemental areas of which vary between black and white corresponding to the original.

8. In a system for the transmission of pictures by electricity, a source of carrier waves, means to modulate carrier waves from said source to produce modulated carrier waves having amplitudes which vary between two finite limiting values, neither of which is zero, corresponding to variations in the tone values of elemental areas of a picture between black and white, and detecting means for producing from said modulated carrier waves a picture the tone values of the elemental areas of which vary between black and white and have intermediate tone values.

9. In a system for the transmission of pictures by electricity, a source of carrier waves, means to modulate carrier waves from said source to produce modulated carrier waves having amplitudes which vary linearly between two finite limiting values, neither of which is zero, corresponding to variations in the tone values of elemental areas of a picture between black and white, and detecting means for producing from said modulated carrier waves a picture the tone values of the elemental areas of which vary between black and white and have intermediate tone values.

In witness whereof, we hereunto subscribe our names this 14th day of May, A. D. 1924.

HERBERT E. IVES.
